UNITED STATES PATENT OFFICE.

FRED A. BOWE, OF SOUTHBRIIDGE, MASSACHUSETTS.

HOUSE SLIPPER AND METHOD OF MAKING IT.

Application filed September 29, 1924. Serial No. 740,488.

This invention relates to a house slipper or a slipper of the type sometimes called "bed-room" slipper. The principal object of this invention is to provide a method of manufacturing a slipper of this type having its upper formed of sheepskin, with the wool on it and turned inside in such a way that a hard stiff sole can be provided instead of the usual soft one and to connect the upper with the sole in such a way that the sole does not have to be trimmed, set or finished after the upper is applied to it and it does not project beyond the upper or any point around it. This latter feature is particularly important in this class of slippers because they are often worn in bed and the hard sole is important because that extends their use materially so that they can be worn outdoors or even driving a car.

Other objects and advantages of the invention will be set forth hereinafter.

Reference is to be had to the accompanying drawings in which

Fig. 1 is a transverse sectional view of a slipper as manufactured on the last before it is turned but when it is otherwise completed;

Fig. 2 is a similar view showing the turned slipper in the position in which it is to be worn;

Fig. 3 is a side view of the complete slipper.

Slippers for this general purpose have been made of the same material as this one as far as the upper is concerned, namely, sheepskin with the wool on and turned inside to form a soft and warm slipper, and have been provided with a cuff as 10 formed by turning down the top of the slipper.

This is an ornamental feature but can be rendered useful by turning it up in cold weather to protect the ankle. A detrimental feature about these bed-room slippers as they have been put on the market is that the sole is made of the same material as the upper and both being soft the slipper has no shape. Furthermore, the seams where the parts of the sole and upper are connected are on the outside and present a rough appearance.

They are ordinarily overcast to partly disguise their real appearance but that is only a small improvement and furthermore the overcast stitches give way after a short time and the appearance of course is worse than if they had not been used.

For the purpose of overcoming these dif-

ficulties and more especially providing the hard sole in such a form that it does not project beyond the upper at any point and is located entirely within the actual area of the sole that is utilized to support the foot I have provided the following way of manufacturing such a slipper. I take a single piece 11 of sole leather or other comparatively hard and stiff material, shaped to the outline and size which is desired, and set, trim and finish the edges all around. Then I apply the upper to it. This in itself is a radical change in this industry because heretofore the sole has been made rough at the edge, the upper has been applied and the shoe turned and then the sole has been trimmed, set and finished on the complete shoe. This has not been difficult heretofore because the sole projected beyond the upper and was readily available for the coloring, finishing and polishing operation.

Another feature of the sole 11 is that I provide it with the usual channel 12 around the edge on the inside flat surface but this channel is narrower than usual and extends up to about $\frac{1}{6}$ of an inch of the vertical edge around this sole. This is an important difference over the usual channel because that is made at a considerable distance from the edge of the sole and away inside the edge. It leaves the edge projecting and permits of the trimming and finishing of the edge after the slipper is otherwise completed. As it is not known just how much finish has got to be taken off at either side or whether it all has to be taken off at one side it has been necessary to space this channel very far from the edge.

However, with my method of manufacture, the edge being trimmed and finished to its final form before the sole is channeled, I can make the channel just where I want it and have it a uniform distance from the edge all around, as the edge is used as a guide. I can also bring it up substantially to the edge as shown. These two features of the invention thus co-operate to produce a practical slipper for this purpose.

Now I take the upper 13 which consists of the ordinary pieces of sheep-skin with the wool on it trimmed to a uniform thickness and sew the two pieces together at the front and rear with the rough edges on the wool side. While in the position in which these seams are sewn, namely with the wool side out, I place it under the sole 11 on the last

14 with its edge projecting over the sole and with the ordinary machinery well known in this art sew its edge all around the sole in the channel 12 by a row of stitches 15. These 5 stitches are only about a sixteenth of an inch from the edge of the sole and they hold the inner edge of the upper down to the sole all around and at its extreme edge. For 10 this reason the edge of the sole cannot project out beyond the bottom of the upper when the shoe is finished as is shown in Fig. 2 which illustrates the slipper after it is taken off the last 14 and turned. An insole 16 is provided of the same material as 15 the upper but there is no hard in-sole and the sole itself consists of a single piece of leather. This constitutes an important economy as it avoids the use of two pieces 20 of leather for the hard sole and cutting out and handling them.

The slipper as completed really has a double purpose. It serves the purpose of a bed-room or sleeping slipper as it can be worn to bed and it has no sole projecting out 25 beyond it to tear the bed-clothes or render it uncomfortable to the wearer. It has all the softness inside of any of the ill-looking bed-room slippers now on the market, but in addition to these features it has an attractive appearance so that it can be worn in 30 the presence of others and has a hard enough sole so that it can be worn for a short trip out-doors even on cold ground and furthermore the sole is hard and stiff enough so that 35 it can be used in driving a car. The method of manufacture is a departure from anything with which I am familiar in this art. Heretofore the soles have been shaped and 40 trimmed after the shoe was otherwise complete whereas by this method I trim them, set and place them for channeling first and the channeling co-operates with this feature as has been explained above.

Although I have illustrated and described 45 only one process of manufacture and one specific slipper I am aware of the fact that modifications can be made in both without

departing from the scope of the invention as expressed in the claims. Therefore I do not wish to be limited to all the details of construction herein shown and described, but what I do claim is:—

1. The method of making a house slipper which consists in first forming a sole having the exact outline and size desired, then finishing the edge of said sole as it is to be in the completed product, channeling the top surface of the sole in an outward direction to a line all around the edge as near as possible to the finished edge of the sole, thereafter bending the edge of an upper around the channel flap and in under it into said channel and securing it to the channel flap, and then turning the slipper.

2. The method of making a house slipper which consists in first cutting out a sole, then finishing the edge of said sole to the size and shape desired for the completed product, channeling the top surface of the sole to a line all around the edge close to the finished 70 edge of the sole to form a channel flap, sewing the edge of an upper in turned position to said flap and into said channel and on the outer surface thereof, then turning the slipper to bring the upper out over the wall 75 of the channel, and applying an in-sole to the top of the sole over the inner edge of the upper and channel flap, said in-sole being of flexible sheep-skin with the wool thereon.

3. As an article of manufacture, a house slipper comprising a sole consisting of a single piece of leather having a finished edge and a channel in the top extending substantially to that edge and an upper of sheep-skin with the wool on the inside secured at its edge in said channel and extending out over the edge of the sole all around so that said edge of the sole cannot project beyond the upper at any point.

In testimony whereof I have hereunto affixed my signature.

FRED A. BOWE.
